Claims priority, application Italy June 21, 1950

2 Claims. (Cl. 122—235)

The present invention relates to heat exchangers.

With known heat exchangers made up of spaced tubes, there is a large area of contact provided by the outer surfaces of the tubes, but on the other hand there is very little turbulence in the fluid so that the best possible heat exchange does not take place. Baffles are required for guiding the fluid on the outside of the heat exchanging tubes in desired directions. Where finned heat exchanging elements are provided, any advantage to be derived from such elements is largely nullified by the fact that such elements are extremely difficult to clean because of the small spaces between the fins and as a consequence foreign bodies accumulate in the spaces between the fins and greatly detract from the heat transferring properties of such elements.

One of the objects of the present invention is to overcome the above drawbacks by providing a heat exchanger which includes the characteristic advantages of tubular heat exchanger elements and at the same time provides a high turbulence in the fluid at the exterior of the heat exchanging elements so as to promote an efficient transfer of heat.

Another object of the present invention is to provide a heat exchanger unit which requires a minimum number of baffles for directing fluid in a desired direction.

A further object of the present invention is to provide a heat exchanger which increases the rate of fluid flow in the direction of fluid flow so that as the temperature of the fluid decreases its rate of movement increases to compensate for a drop in the temperature of the fluid.

With the above object in view the present invention mainly consists of a heat exchanger apparatus which includes a plurality of spaced walls each of which is made up of a plurality of parallel tubes engaging each other along the lengths thereof and extending in a direction perpendicular to the direction of a fluid flowing between the spaced walls so as to provide a turbulence in this fluid. The spaced walls define for this fluid a passage which decreases in cross-section in the direction of fluid flow so that the rate of fluid flow increases in the direction of fluid flow to compensate for a drop in the temperature of the fluid.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is in elevational view of a preferred embodiment of the present invention, Fig. 1 showing the structure of Fig. 3 as seen from the lower side of Fig. 2 with the lower wall of Fig. 2 removed to show the arrangement of tubes behind this wall; and

Fig. 2 is a plan view of the apparatus down in Fig. 1 taken along line 2—2 of Fig. 1 in the direction of the arrows.

2

Referring to the drawings, in which a preferred embodiment of the present invention is illustrated, it will be seen that the heat exchanger apparatus of the present invention comprises a plurality of spaced heat exchanging walls

5 14 which are adapted to guide a first fluid or the hot combustion gases produced in a combustion chamber, not shown in the drawings, along a predetermined path extending from the left end of the wall portions 14, as viewed in the drawings, to the opposite end of the wall portions along the spaces therebetween as indicated by the wavy arrows in Figs. 1 and 2. The walls 14 are each made up of a plurality of parallel, vertically extending tubes which engage each other along the lengths thereof and which are connected at the top and bottom ends to 15 headers 15. The headers 15 have baffles 17 located in the interior thereof so that the water or other liquid in the tubes move in the direction of arrows V shown in Figs. 1 and 2. The heat exchanger walls 14 are respectively located along planes which converge towards each other 20 in the direction of fluid flow so that the spaces between the wall portions 14 decrease in the direction of fluid flow, whereby the speed of flow of the hot combustion gases is increased as these gases flow along the wall portions 14 so that the gases are compelled to move with increasing speed through the decreasing spaces to compensate for the drop in temperature of the gases as they approach the right ends of the wall portions as viewed in Figs. 1 and 2, that is, as the gases move towards the chimney not shown in the drawings. Since the wall portions 14 25 are formed from the plurality of parallel tubes which engage each other along the length thereof, the outer surfaces of these wall portions will be similar to fluted or corrugated surfaces so as to promote turbulence in the gases flowing through the spaces between the wall portions in a direction normal to the direction in which the tubes extend. This turbulence in the hot combustion gases flowing between the wall portions and the increasing speed with which these hot gases are forced to flow between the walls 14 increase in a highly novel manner 30 the heat exchange between the first fluid or the combustion gases flowing between the wall portions 14 and the second fluid located in the tubes from which the wall portions 14 are formed.

It will be understood that each of the elements described above, or two or more together, may also find a useful application in other types of heat exchangers differing from the types described above.

While the invention has been illustrated and described as embodied in a heat exchanger having walls formed of tubes which produce turbulence and which act as baffles, it is not intended to be limited to the details shown, since various modifications and structural changes may be made without departing in any way from the spirit of the present invention.

55 Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by 60 Letters Patent is:

1. Heat exchanger apparatus comprising, in combination, a pair of spaced wall portions located opposite each other and adapted to guide a first fluid along a predetermined path extending from one end of said wall portions 65 to an opposite end of said wall portions along the space therebetween, each of said wall portions comprising a plurality of tubes which engage each other along the

length thereof and extend in a direction normal to said predetermined path so as to present to said first fluid a corrugated surface whose corrugations are normal to said path, whereby a turbulence is produced in said first fluid by said wall portions to enhance the heat transfer between said first fluid and a second fluid in said tubes of said wall portions, said wall portions gradually approaching each other from said one end thereof to said opposite end thereof along said predetermined path so that the space between said wall portions decreases, whereby the speed of flow of said first fluid is increased along said path to enhance the heat exchange with said second fluid as the temperature of said first fluid decreases.

2. Heat exchanger apparatus comprising, in combination, a pair of spaced wall portions located opposite each other and adapted to guide a first fluid along a predetermined path extending from one end of said wall portions to an opposite end of said wall portions along the space therebetween, each of said wall portions comprising a plurality of tubes which engage each other along the length thereof and extend in a direction normal to said predetermined path so as to present to said first fluid a corrugated surface whose corrugations are normal to said path, whereby a turbulence is produced by said first fluid by

said wall portions to enhance the heat transfer between said first fluid and a second fluid in said tubes of said wall portions, said wall portions being located in non-parallel planes so that said wall portions gradually approach each other from said one end thereof to said opposite end thereof along said predetermined path so that the space between said wall portions decreases, whereby the speed of flow of said first fluid is increased along said path to enhance the heat exchange with said second fluid as the temperature of said first fluid decreases.
